[57] CLAIM

The ornamental design for a concrete block inspection screen design, as shown.

DESCRIPTION

FIG. 1 is a top front perspective view of my new concrete block inspection screen;

FIG. 2 is a right side elevation;

FIG. 3 is a front elevation;

FIG. 4 is a top plan view;

FIG. 5 is a bottom plan view;

FIG. 6 is a left side elevation; and,

FIG. 7 is a rear elevation.

The discontinuous showing of the wire mesh is for ease of illustration. It is understood that the wire mesh is continuous throughout the entire claim.
